Dec. 786

Nicholas Muller of New York, N. Y.
Letters Patent No. 786. Dated April 29th 1856.

The Schedule referred to in these Letters Patent, and making part of the same.

To all whom it may concern:

Be it known that I, N. Muller, of the City, County, and State of New York, have invented or produced a new and original design for block case fronts; And I do hereby declare that the following is a full, clear and exact description of the same, reference being had to the annexed drawings, making a part of this specification, in which,

Fig. 1. is a face view of a clock case front showing my design.

Fig. 2. is a side view of do.

Fig. 3. is a transverse section of do, (x)(x), fig. 2, showing the plane of section.

Similar letters of reference indicate corresponding parts in the several figures.

A, represents a circular opening in the case front, which opening exposes the dial of the clock.

The opening A, is surrounded by a wreath B, formed of a grape vine, the leaves, fruit,

and stalks, being disposed or arranged as shown in fig. 1, and having a cupid C, on its upper part directly over the opening A.

Underneath the opening A, there are two figures D, D, in a sitting posture, and between which the opening E, which exposes the pendulum bob is placed, as clearly shown in fig. 1.

The wreath and figures are formed in relief upon the case front, as shown in figs. 2 and 3.

What I claim as new and desire to secure by Letters Patent, is

The wreath B, and figures C, D, D, arranged as herein shown and described, and forming a new and ornamental design for a clock case front.
